UNITED STATES PATENT OFFICE.

JOHN K. ROGERS, OF BROOKLINE, MASSACHUSETTS.

DESIGN FOR A FONT OF PRINTING-TYPE.

SPECIFICATION forming part of Design No. 12,035, dated November 16, 1880.

Application filed March 1, 1880. Term of patent 3½ years.

To all whom it may concern:

Be it known that I, JOHN K. ROGERS, of the town of Brookline, in the State of Massachusetts, have invented and produced a new and original Design for a Font of Printing-Types, of which the following is a specification, the nature of the design being clearly shown in the accompanying typographical impressions, to which reference is made.

10 My design consists of an alphabet of capital letters with figures, points, short-and, and dollar-mark, of the style called "condensed gothic," each character having a line across the lower part, these lines forming a connection when a word is composed, and giving

15

the effects of a continuous score under the whole word.

My invention, as above described, may be considered as an alteration or improvement on my Design Patent No. 10,752, substituting bottom line only for top and bottom lines and end pieces, &c., and thereby making a new design.

What I claim as new is—

A font of printing-type, substantially as shown.

JOHN K. ROGERS.
